METHOD OF AND MACHINE FOR GRINDING IN VALVES AND COCKS

Filed Oct. 24, 1929

Inventor:

KARL MARTIN

By D. P. Wachanwitz, M.D.

UNITED STATES PATENT OFFICE

KARL MARTIN, OF GLOGAU, GERMANY

METHOD OF AND MACHINE FOR GRINDING IN VALVES AND COCKS

Application filed October 24, 1929, Serial No. 402,267, and in Germany August 18, 1928.

My invention relates to the art of grinding in or of regrinding valve bodies or plugs so as to make them fit snugly in the valve casing or seat. In carrying out such a grinding operation manually, the casing or seat usually is fixed and held in fixed position, while the valve body or plug is repeatedly forced into the fixed casing or onto the seat more or less violently and, at the same time, slight oscillatory movement is imparted to the body of the valve or the plug while the force or pressure exerted on the valve body or plug is gradually decreased.

In manipulating a valve body or plug in this way for the purpose of grinding the same in the seat the amplitude of the reciprocatory or rotary movement thereof, that is to say, the length of the single grinding action or course will depend upon the leakage of the valve or cock, due to wear. In case of valves or cocks of large size or if the valve or cock under treatment leaks very freely, the operator must apply a more intensive pressure and cause the valve body or plug to perform oscillations of a greater amplitude than if a valve or cock of small size or which leaks moderately only, is to be repaired or attended to.

According to the present invention the grinding operation is accomplished by means of a particular machine adapted to work in strict imitation of the above described manual operations as far as this can be done mechanically; consequently, the said machine is constructed and arranged in a manner that the pressure exerted by the valve body or plug on the valve casing or seat, can be changed so as to be greatest or of greatest intensity first or immediately upon forcing the body or plug inward and to then be gradually decreased automatically, and that also the amplitude or length of the grinding course can be varied.

Another feature of the machine constructed for carrying out the grinding operation in the manner herein pointed out, resides in the provision therein of a plurality of grinding devices adapted to be individually stopped and put out of operation without thereby interrupting or affecting the operation of the other devices or the machine as a

whole, so that each workpiece (valve or cock) can be readily removed from the machine when finished and replaced by another one, whereby the efficiency of the machine will be greatly improved.

A further object of my invention is to provide a particular chuck for clamping and holding the valve or cock to be ground.

I am aware that machines for regrinding valve or cocks are universally known, but as far as my knowledge goes the hitherto suggested machines operate in a manner which is entirely distinct from the mode of operation of my improved machine. In a known type of valve grinding machines the valve member to be reground is caused to rotate permanently in one direction whereby fine grooves are likely to be produced in the co-operating surfaces of the valve or cock, and in another class of known valve grinding machines the necessary pressure to be applied to the moving valve member, is produced by springs or weights so that the pressure cannot be changed or adjusted, or, after the machine has been stopped, only in a manner which will be very troublesome, while any such adjustments of the pressure cannot be effected in machines of this known class during the grinding operations. Further all of the known machines are constructed and arranged to provide only one or at best two grinding facilities or devices and require stopping as a unit when a valve or cock has been finished and a new one is to be inserted.

I will now proceed to describe my invention more in detail in connection with the embodiments thereof constituting the machine and illustrated on the accompanying drawing, it being intended and understood that the invention is illustrated by, but not limited to the embodiments thereof so illustrated and described.

A preferred and practical embodiment of the invention is shown in the accompanying drawing, in which:

Figure 1 is a view in side elevation of the machine, partly in section on the line I—I of Figure 2 which is a view in top plan of the same;

Figure 3 is a view in cross-section taken

on the line III—III of Figure 2 with a cam shaft mounted on and above the table.

Referring to the construction of the machine shown in Figures 1 to 3 the intermediate shaft 2 and the cam shaft 3 are driven by means of the pulley 1 and suitable belting or in any other, appropriate manner. Keyed to the shaft of the driving pulley 1 is a crank-disk 4 provided with a radially adjustable pin 5 pivotally connected with a push-rod 6 the other end of which engages a rack 7 mounted so as to be displaceable lengthwise in a horizontal plane. According to the adjustment of the crank pin 5 of the disk 4 the rack 7 will be moved or displaced horizontally more or less in the one or the other direction and, as the rack 7 is in engagement with two or several toothed wheels 8 each keyed to a vertical grinding shaft 9, the said wheels 8 and the shaft 1 will be caused, by the movements of the rack 7 to revolve in the one or the other direction depending upon the direction in which the rack moves. The toothed wheels 8 are adapted to be disengaged from the rack 7 by means of hand levers 10, a separate lever being provided for each wheel 8. The wheels 8 are mounted on the lower square end of the shafts 9 so as to be capable of sliding thereon in axial direction for engagement with short square studs 11 fixed to or integral with a horizontal bar 12 rigidly connected with the framing of the machine.

When the toothed wheel 8 has been shifted lengthwise on its supporting shaft 9 and its square hub portion caused to engage the square stud 11, the shaft 9 will be locked and prevented from rotation. The upper or free end of the shaft 9 is provided with a means, such as a threaded pin 9' or the like, for detachably connecting a valve body or a plug to be reground with the shaft 9, see Fig. 3, so that when the corresponding toothed wheel 8 has been put in gear, the valve body or plug will be caused by the shaft to reciprocate simultaneously and in unison with the reciprocatory movements of the shaft.

Firmly attached to the table of the machine and located to coaxially surround the upper end of the shaft 9 is a supporting basket 13 for the accommodation of the casing of the valve or cock to be reground and for firmly holding the same during the grinding operation. It goes without saying that separate baskets are provided in the machine one for or in connection with each shaft 9, and that the baskets are constructed and shaped to conform to the particular shape and size of the valve or cocks to be reground.

Journalled in suitable bearings on the table and parallel thereto is the cam shaft 3 which is equipped with as many cams 14 as grinding shafts 9 are provided in the machine, and the cams 14 are located in front of the shafts 9, as will be seen in Figure 2.

Intermediate between the shaft 9 and the cam 14 there is fixed to the table a lug 15 with a pin 16 serving to pivotally support or fulcrum a single-armed lever 17 and a two-armed lever 18. Mounted in the lever 17 is a threaded spindle 19 the lower end of which engages and rests upon one arm of the other lever 18. The lever 17 is of sufficient length to normally project into the path of the cam 14 so that when the shaft 3 revolves, the cam 14 will move the lever 17 downward. The amplitude of this angular movement of the lever 17 about its pivot 16 can be controlled and adjusted at any time by means of the threaded spindle or screw 19 and as the lever 18 is actuated by the lever 17, also the operating amplitude or angle of oscillation of the lever 18 can be controlled and adjusted during the operation of the machine by means of the screw 19.

The outer arm of the lever 18 is shaped to form a fork engaging in an annular groove provided in the peripheral surface of a cylindrical ring 20 adapted to support the casing of the valve or cock to be ground and which encloses the bearing bushing 21 of the grinding shaft 9. The ring 20 is lifted or displaced upward by the lever 18 operated by the cam 14 and lever 17 during each revolution of the shaft 3, that is, each time the direction of the movement of the rack 18 changes. The casing 22 of the valve or cock to be reground rests in the basket 13 above the supporting ring 20, with slight free play, so as to be adapted to be removed and raised from the valve body or plug to be ground in, once in each revolution of the cam shaft 3.

It will be seen that the force of the impact of the casing dropping back onto the valve body or plug after such raising movement and consequently the initial grinding pressure will depend upon the distance or height the casing had been lifted from the mating valve body or plug.

The grinding operation or process comprises two stages. In the first stage or period an adjustable grinding pressure of greater force will be applied while in the second stage or period a continuous low grinding pressure prevails which will substantially correspond to the gravity or weight of the casing to be reground. In this way an absolutely perfect and excellent grinding effect will be attained, similar to hand work, and binding, sticking or jamming between the casing and the valve body or plug cannot occur. The lifting altitude or "stroke" of the casing which is equivalent to the impact force of the dropping casing and consequently the initial grinding pressure may be varied in a ready, efficient manner during operation by varying or adjusting the position of the lever 17 with relation to the lever 18, by means of the set screw 19.

In case of grinding valves or cocks which are excessively worn out and leaky, the grinding stroke, that is to say, the revolving angle or stroke of the grinding shaft 9 may be increased to a maximum in addition to the described increase of the grinding pressure. This can be done in a simple way after the machine has been stopped by adjusting the crank pin 5 so that the same will occupy its extreme outermost position in the disk 4 whereby the stroke of the rack 7 or the horizontal reciprocation thereof will be a maximum and also the angular movement or reciprocation of the wheels 8 will come to a maximum.

As regards the operation of the machine it is immaterial whether the casing of the valve or cock is fixed and the valve body or plug is caused to oscillate or, vice versa, the latter is fixed and the casing caused to alternately revolve in both directions.

My invention in its broadest aspect is not limited to the particular construction shown and described, nor to any particular construction by which it has been or may be carried into effect as many changes may be made therein without departing from the main principle of the invention and without sacrificing its chief advantages.

I have not attempted to explain all of the minute details of the construction of the machine, for it will be understood by those to whom this specification is addressed that the parts will be of the proper size and relationship, and will be properly mounted and supported according to the tenets of machine construction; nor have I attempted to illustrate the parts in their exact sizes and dimensions as many of the parts are conventionally shown.

It is unnecessary to reiterate the operation of the machine, for the operation of the several parts has been described in detail. Nor does it seem necessary to burden this specification with a full exposition of the advantages which the invention possesses, for they have been partly discussed in the introductory portion of this specification and, in all other respects, will be apparent to those skilled in the art to which this invention pertains.

What I claim is:—

1. A valve grinding machine comprising a support for a member having a valve seat, a support for a valve to be ground against the seat of said member, rack and pinion means for oscillating the latter support, cam means for reciprocating the first mentioned support to alternately move the member having the valve seat away from and into engagement with the valve, and means for varying the amplitude of reciprocation of said first mentioned support, said last named means comprising a pair of levers between the cam and the first mentioned support cooperating with

said support and said cam and each other to transmit movement of the cam to the support, and adjustable screw means to vary the movement imparted to said levers by said cam.

2. In a valve grinding machine, a vertically movable support for a member having a valve seat, a support for a valve to be ground against the seat of said member, means for oscillating the latter support, a cam, an intermediate pivoted lever engaged at one end with said first mentioned support, another lever pivoted at one end and having its other end disposed for cooperation with said cam, and a screw member carried by said second mentioned lever whereby the cam is adapted to effect reciprocation of said first mentioned support and whereby the amplitude of the reciprocations of said first mentioned support may be varied.

3. In a valve grinding machine, means for supporting a member having a valve seat, an oscillatory shaft for supporting a valve to be ground against the seat of said member, a reciprocal rack, a gear splined to said shaft for movement between two positions in one of which it meshes with said rack and in the other of which it is disengaged from said rack, means with which said gear is engageable in its latter position to hold the shaft against oscillation, and means for shifting said gear between said two positions.

In testimony whereof I have affixed my signature.

KARL MARTIN.
